CLAIM

The ornamental design for an interior of cabin for construction machine, as shown and described.

DESCRIPTION

FIG. 1 is a perspective view of an exterior of a cabin for construction machine depicting environmental subject matter which does not form part of the claimed design;

FIG. 2 is a front view of the exterior of a cabin for construction machine;

FIG. 3 is a rear view of the exterior of a cabin for construction machine;

FIG. 4 is a top plan view of the exterior of a cabin for construction machine;

FIG. 5 is a bottom plan view of the exterior of a cabin for construction machine;

FIG. 6 is a right side elevational view of the exterior of a cabin for construction machine;

FIG. 7 is a left side elevational view of the exterior of a cabin for construction machine;

FIG. 8 is a cross-sectional view of an interior of cabin for construction machine showing our new design, taken along line 8-8 in FIG. 2 with some internal structure omitted;

FIG. 9 is an enlarged view of an interior of cabin for construction machine showing the portion defined by crop line 9-9 in FIG. 8;

FIG. 10 is an enlarged cross-sectional view of an interior of cabin for construction machine showing the portion defined by crop line 9-9 in FIG. 8, taken along line 10-10 in FIG. 2; FIG. 11 is an enlarged cross-sectional view of an interior of cabin for construction machine showing the portion defined by crop line 9-9 in FIG. 8, taken along line 11-11 in FIG. 2; FIG. 12 is an enlarged cross-sectional view of an interior of cabin for construction machine showing the portion defined by crop line 9-9 in FIG. 8, taken along line 12-12 in FIG. 8; and,

FIG. 13 is an enlarged cross-sectional view of an interior of cabin for construction machine the portion defined by crop line 9-9 in FIG. 8, taken along line 13-13 in FIG. 8.

The features shown in broken lines in the drawings depict environmental subject matter only and form no part of the claimed design.
